UNITED STATES PATENT OFFICE.

CHARLES T. FLETCHER, OF WORCESTER, MASSACHUSETTS, ASSIGNOR TO
THE LOCOMOBILE COMPANY OF AMERICA, OF NEW YORK, N. Y.

DESIGN FOR A PUMP-CASING.

SPECIFICATION forming part of Design No. 33,051, dated August 7, 1900.

Application filed April 25, 1900. Serial No. 14,357. Term of patent 14 years.

To all whom it may concern:

Be it known that I, CHARLES T. FLETCHER, of Worcester, in the county of Worcester and State of Massachusetts, have invented and produced a certain new and original Design for a Pump-Casing, of which the following is a specification, reference being had to the accompanying drawing, forming a part thereof.

This design relates to the casing of a pump and is shown in the accompanying drawing, which is a perspective view of the pump-casing.

My design consists in the novel form or configuration of the pump-casing 1, and its distinguishing features are as follows: 2 is the

stem of the casing. 3 3 are arms branching divergently from stem 2 and forming therewith a Y, and 4 is a short branch or protuberance located at the apex of the arms 3 3 in line with the main part or body of stem 2. 20

I claim—

The design for a pump-casing, substantially as herein shown and described.

In testimony whereof I have affixed my signature in presence of two witnesses.

CHARLES T. FLETCHER.
